DISPENSING DEVICE

Henry K. Ullman, Washington, D. C.

Application February 25, 1938, Serial No. 192,653

6 Claims. (Cl. 91—47)

My invention relates to dispensing devices and more particularly to containers adapted to supply fluid materials, and specifically an adhesive such as mucilage, in a convenient manner.

Heretofore the handling of mucilage has been done in a most inconvenient manner, either by requiring the operator to insert a brush into a mucilage container, or by supplying the container with a rubber cap having a small slit therein through which the mucilage may seep upon the appliance of pressure to said cap when said container is in an inverted position. In both of these methods the mucilage is prone to harden, either on the brush or around the slit in the rubber cap and consequently cause considerable difficulty and discomfort to an operator attempting to coat the proper amount of mucilage upon an article.

Having in mind the defects of the prior methods, it is an object of my invention to provide a dispensing container for an adhesive such as mucilage that is simple in both operation and construction.

It is another object of my invention to provide a dispensing container for mucilage that is adapted to readily supply the proper amount of mucilage at all times.

It is still another object of my invention to provide a dispensing container for mucilage that is readily operated and/or cleaned without causing the operator to soil his hands.

It is a further object of my invention to provide a dispensing container for mucilage that will provide a given flow of the mucilage regardless of the amount of mucilage, above a certain minimum, within the container.

It is a still further object of my invention to provide a dispensing container for adhesives arranged and adapted so that an article to be coated is applied to a flat operating table on the device rather than the device being applied, in an inverted position, to the article.

The foregoing objects and others ancillary thereto I prefer to accomplish as follows:

I provide a container having an upper wall forming a flat operating surface and having means for dispensing material from within said container onto said table.

According to a preferred embodiment of my invention, I provide a container comprising a hollow base having a flat upper surface forming an operating table upon which mucilage may be flowed so that an object or sheet may be rubbed or daubed therein to be coated with the proper amount of mucilage. Mounted on the rear of

this base is a reservoir adapted to contain mucilage which may be flowed onto the operating table by the force of gravity. Feeding apertures may be located in the operating table through which the mucilage may flow, and a vent is provided in the reservoir to permit the displacement of said mucilage.

The flow of the mucilage onto the operating table is controlled by a lever system connected to valves associated with said feeding aperture and said vent. This lever system is located within the base and the reservoir. An adjustable bar is mounted upon the operating table, whereby the mucilage may be spread over the table or any mucilage which may be left thereon may be readily scraped off, whether in the fluid or hardened state.

The novel features that I consider characteristic of my invention are set forth with particularity in the appended claims. The invention itself, however, both as to its organization and its method of operation, together with additional objects and advantages thereof will best be understood from the following description of a specific embodiment when read in connection with the accompanying drawing, in which like reference characters indicate like parts throughout.

Fig. 1 is a front view in elevation of my adhesive dispensing device;

Fig. 2 is a side view in elevation of my adhesive dispensing device;

Fig. 3 is a view in cross section taken along the line 3—3 of Fig. 1; and

Fig. 4 is a side view in elevation and partial cross section of a modified form of my dispensing device incorporating a modified form of scraper.

An adhesive dispensing device to overcome the defects hereinbefore enumerated must have at least two totally distinct characteristics; it must be capable of providing a predetermined flow of adhesive; and it also must be provided with means for cleaning the container around the dispensing aperture. Accordingly, a preferred embodiment of my invention, referring to Fig. 1 of the drawing, is constituted by a container comprising a hollow base 1 supporting a reservoir 2 on its rear portion. The base 1 is provided with a flat upper surface or operating table 3 upon which adhesive may be flowed and an object or sheet may be rubbed therein to be coated with said adhesive.

The base 1 is also provided with a flat bar 4 which is adapted to slide along the surface of the operating table 3. This flat bar 4 is pivotally

supported at its ends by arms 5 adapted to slid-
ingly cooperate with ribs 6 extending longitudi-
nally along the upper edge of the side walls of
the base 1. The bar 4 is provided with a handle
5 4' whereby it may be tilted and moved over the
surface of the table 3. If the bar 4 is tilted
slightly away from the surface of the table 3 it
will act as a spreader to spread an even layer
10 of adhesive over the table. On the other hand,
if the bar 4 is tilted tightly against the surface
of said table 3 it will act as a scraper to remove
any surplus adhesive that may have accumulated
from time to time.

Another type of adhesive contacting bar is
15 shown in Fig. 4. This modification comprises
a pivotal bar 30 that is supported at one end by
an upright pin 31 that is seated in the upper wall
3 of the base 1. A handle 32 is mounted on the
opposite end of the bar 30 from the pin 31 so that
20 said bar 30 may be readily swung on said pin
31. The pin 31 is provided with a head 33 that is
spaced from the upper edge of said bar 30. By
this means said bar 30 may be lifted slightly to
spread the adhesive over the table 3 or the bar
25 may be pressed tightly against the surface of
said table 3 to scrape the adhesive therefrom.

The reservoir 2 is provided with a convenient
30 supply opening in the form of a threaded neck 7
and a screw cap 8, to permit the ready filling of
said reservoir with a fresh supply of mucilage.
A vertical tubular housing 9 is associated with
the reservoir 2 and extends down to and in com-
35 munication with hollow base 1. This tubular
housing 9 is adapted to contain a valve control-
ling mechanism that will be more fully described
hereinafter.

As shown in Fig. 3, the reservoir 2 may be sup-
plied with an adhesive such as mucilage M. The
40 reservoir 2 is in communication with the hollow
base 1 by means of an opening 10 extending
through the wall between said members. A sup-
ply aperture 11 is located in the center of the
operating table 3 to permit a flow of mucilage M
45 from the reservoir through the opening 10 and
the hollow base 1 to the operating table 3.

The flow of the mucilage through this aperture
11 is controlled by a valve 12 which is mounted
upon a lever 13. The lever 13 is fulcrumed on
a stud 14 and pivotally connected, by a pin 15,
50 to a plunger 16 located within the tubular hous-
ing 9. The plunger 16 is provided with a piston
17 to prevent the mucilage from flowing upwardly
into the tubular housing 9, or the air within the
housing from seeping down into the mucilage
55 chamber and thereby cause the mucilage to
harden. Furthermore, this piston 17 acts to ac-
celerate the pressure upon the mucilage upon
the opening of the supply aperture 11 as will be
more fully disclosed hereinafter. As shown in
60 Fig. 4, the operating table 3 may be provided with
a plurality of supply openings 11 and cooperat-
ing valves 12.

The plunger 16 extends upwardly through the
65 top of the tubular housing 9 and thence through
an air vent chamber 18 extending from the wall
of the reservoir 2. This chamber is provided
with a vent 19 that is controlled by a valve mem-
ber 20 carried by the plunger 16. A finger piece
70 21 is fixed on the plunger 16 adjacent the valve
member 20. A helical spring 22 is coiled about
the plunger 16 and cooperates with the upper
wall of the tubular housing 9 and the finger piece
21 to resiliently retain said plunger 16 in its
75 upper position, wherein the valve 12 acts to seal

the mucilage supply aperture 11 and the valve
20 acts to seal the air vent 19.

The operation of my device should be readily
understood in view of the foregoing description.
When an operator wishes to coat an article or
sheet with mucilage, he merely presses the finger
piece 21. This action depresses the plunger 16
5 against the force of the spring 22, thereby re-
moving the valve 20 from the air vent 19, and
pivoting the lever 13 on its fulcrum 14 to remove
the valve 12 from the mucilage supply aperture
10 10 15 11. The mucilage M is thereby permitted to flow
through the aperture 10 into the hollow base 1
and through the supply aperture 11 on to the
operating table 3.

This flow is aided by the opening of the vent
19 to permit the passage of air into the upper
portion of the reservoir 2 to displace the mucilage
which is permitted to flow therefrom. Furthermore,
as the plunger 16 is depressed the piston 17
20 is suddenly forced down against the mucilage
within the tubular housing 9, thereby acceler-
ating the pressure of the mucilage at the supply
aperture 11, and increasing the head of the sup-
ply mucilage M within the reservoir 2. This
accelerated force will cause the mucilage to im-
mediately flow through said supply aperture 11.
25

When a sufficient amount of mucilage has
been permitted to flow upon the operating table
3, the operator may release the finger piece 21
30 to stop the flow of mucilage. The compressed
helical spring 22 then acts to return the plunger
16 and lever 13 to their normal positions, thereby
closing the mucilage supply aperture 11 and the
air vent 19 with the valve 20. The operator may
35 then spread the mucilage, if he so desires, by the
use of the bar 4, and rub or dab the article in
said mucilage, whereby the article becomes even-
ly coated with the mucilage M in a sufficient but
not excessive quantity.
40

If a surplus of mucilage is withdrawn or
flowed upon the surface 3 and is permitted to
harden thereon, the next operator may readily
remove this surplus merely by tilting the bar 4
45 tightly against the surface of the table 3 and
sliding it therealong. The supporting arms 5,
engaging the ribs 6, will guide the bar 4 over the
surface 3 of the table in close association there-
with so that all of the mucilage may be scraped
50 therefrom. In using the modification shown in
Fig. 4, the bar 30 is merely swung upon the pin
31 by the handle 32.

It is readily evident from the foregoing descrip-
tion that my adhesive dispensing device has many
55 advantages over the prior art. My device is
adapted to provide a sufficient quantity of adhe-
sive to coat an article in the desired manner
without causing the operator to soil his hands.
Furthermore, in coating an article in this man-
ner, a sufficient but not excessive amount of ad-
hesive is applied to the article. Any excess ad-
hesive may be readily removed with the minimum
60 of effort and the maximum of cleanliness, and the
supply of adhesive may always be easily renewed
without great difficulty to the operator.
65

It is to be noted that though I have described
my invention as a dispensing device for adhesives
and specifically mucilage, it is to be understood
that this device may work equally well with other
70 types of materials and for different purposes.
Although I have shown and described certain spe-
cific embodiments of my invention, I am fully
aware that many modifications thereof are possi-
ble. My invention, therefore, is not to be re-
75

stricted except insofar as is necessitated by the prior art and the spirit of the appended claims.

What I claim and wish to secure by Letters Patent in the United States of America is:

- 5 1. A dispensing device comprising a container including a header portion, an upper wall of said container being adapted to form an operating table, a normally closed discharge aperture in said operating table, a normally closed air vent in 10 said header portion, valves for opening said discharge aperture and said air vent, and means within said container for controlling said valves to provide a supply of the material within said container through said discharge opening on to 15 said table, the valve for closing the discharge aperture seating on the underside of the operating table whereby to render the working surface uninterrupted.
- 10 2. A dispensing device comprising a container, an upper wall of said container being adapted to form an operating table, said container having means for providing a supply of the material therein on said operating table, and a bar supported in sliding relation with respect to the 20 surface of the operating table, whereby to contact said material on said table.
- 15 3. A dispensing device comprising a container, an upper wall of said container being adapted to form an operating table, said container having means for providing a supply of the material therein on said operating table, and a pivotally adjustable bar supported in sliding relation with respect to said operating table, whereby said bar may be operated to spread or to remove said material from said operating table.
- 20 4. A dispensing device comprising a container including a header portion, an upper wall of said container being adapted to form an operating table, a discharge opening in said operating table, 25 an air vent in said header portion, valves for closing said discharge opening and said air vent,
- 25 5. A device for dispensing adhesives of the type of liquid rubber cement comprising a container including a header portion, an upper wall of said container constituting an operating table the upper surface of which is normally out of communication with the interior of said container, a valve in said operating table for permitting the flow of adhesive therethrough, an air vent in said header, a spring for normally maintaining said valve and said vent in closed position, and manually operable means for simultaneously opening said valve and said vent, the operating 30 table being fabricated of non-absorptive material, whereby no appreciable amount of adhesive will be retained thereby during periods when the device is not in operation.
- 35 6. A device for dispensing adhesives of the type of liquid rubber cement comprising a container including a header portion, an upper wall of said container constituting an operating table the upper surface of which is normally out of communication with the interior of said container, a plurality of valves in said operating table for permitting the flow of adhesive therethrough, an air vent in said header, a spring for normally maintaining said valves and said vent in closed position, and manually operable means for simultaneously opening said valves and said vent, the operating table being fabricated of non-absorptive material, whereby no appreciable amount of adhesive will be retained thereby during periods when the device is not in operation.

HENRY K. ULLMAN.
